COMBINED TABLE AND SEATING UNIT

John W. Young, Kirkwood, Mo., assignor to Clarin Mfg.
Co., Chicago, Ill., a corporation of Illinois

Filed Feb. 24, 1966, Ser. No. 1,166

Term of patent 14 years

(Cl. D33—14)

The dominant features of my design are shown in solid lines.

I claim:

The ornamental design for a combined table and seating unit, substantially as shown and described.
